Geo. Kennedy
ATTORNEY

UNITED STATES PATENT OFFICE

ALBERTO I. WOODRING, OF WATERLOO, IOWA, ASSIGNOR OF ONE-THIRD TO GEORGE COLVIN KENNEDY, OF WATERLOO, IOWA

ADJUSTABLE FISHING GAFF

Application filed November 25, 1929. Serial No. 409,570.

My invention relates to improvements in adjustable fishing gaffs, and the object of my improvement is to supply for the use of fishermen and others a gaff having a telescoping handle whose entering member is constructed and adapted for frictional and releasable locking engagement with the outer member to hold the gaff in an adjusted position within the handle, and whereby this operation is effected without intrusion of water, sand or sediment into the handle.

This object I have accomplished by the means which are hereinafter described and claimed, and which are illustrated in the accompanying drawings, in which Fig. 1 is a central longitudinal section of the handle part of my fishing gaff, showing the stem of the gaff retracted fully thereinto, and broken away medially, and Fig. 2 is a fragmentary like section of the closed end part of the handle, showing a modified form of the frictional engaging means thereon.

It is to be understood that other modifications may be made in this device which will come within the protection of the appended claims.

The numeral 1 denotes a gaff handle of hollow cylindrical shape, having the imperforate end cap 2 and an opposite centrally apertured end cap 6. On the end cap 2 may be provided a ring 3 to receive links 4 to which a spring snap is connected for use in suspending the device from a belt of the user when desired.

The barrel of the handle 1 is imperforate, and a gaff-hook 8 has a stem 7 mounted slidably and rotatably in the aperture of the other end-cap 6.

On the inner termination of said stem 7 within the barrel 1, is mounted a friction device. As shown in said Fig. 1, this comprises the following coacting elements. An annular clamping ring 9 is fixed on the stem 7 spaced from its end, the latter being threaded. An elastic rubber element 10, longitudinally centrally apertured is mounted on the stem 7, and a clamping ring nut 11 is mounted on the thread of said stem to engage an opposite end of the rubber element 10. A lock nut 12 may be fitted on the thread-

ed end 13 of the stem and secured thereon in an adjusted position.

The clamping ring 11 is caused to compress the abutting end of the rubber body 10, to a sufficient degree, and the nut 12 then secured against it, whereby the rubber 10 may be introduced into the barrel 1 before mounting the end-cap 6 thereon, and so that the body 10 will frictionally engage the inner wall of the barrel somewhat but not resist the pushing of said body through the barrel longitudinally to a desired distance. At this place, the stem 7 may be rotated in a direction to cause it to move through the ring nut 11 to cause the nut to move toward the body 10 to further compress it against the fixed clamping ring 9. This compression of the body 10 causes it to swell outwardly radially all-around to tightly frictionally engage the inner wall of the barrel 1, so that it cannot be moved longitudinally in the barrel except by the exercise of more than an ordinary force. The initial moderate degree of frictional contact of the body 10 with the barrel suffices to hold it with the clamping rings and nut in one position to permit the threaded part 13 of the stem 7 to turn in the nut 11 in effecting this operation. The compression of the body 10 is relaxed by turning the stem 7 in an opposite direction, when the stem may be shifted again longitudinally in the barrel.

In Fig. 1 the body 10 is shown with its ends coned to fit the reentrant coning of the clamping rings 9 and 11. This gives these elements an effective grip upon this elastic body 10 during the compression thereof. In Fig. 2 the coning of the clamping rings and the body 10 is reversed, with like results, but in the latter the periphery of the body 10 is larger than that shown in Fig. 1, considering like masses of the material in both. In Fig. 2, a washer 14 is shown between the clamping ring 11 and the lock nut 12.

No water, dust, sand, or sedimentary or other substances can enter the imperforate handle of the device, so that it will be practicable to use the device in muddy water, or trailing in the water.

The device when the stem 7 is retracted, is shortened so as to be conveniently hung from

the belt of the user, but may be quickly removed, and extended by the means described, for sudden use.

Having described my invention, what I claim as new, and desire to secure by Letters Patent, is:

1. In combination with the shaft of an instrument, a hollow handle therefor comprising a barrel having an imperforate end and an apertured opposite end, said shaft traversing said aperture and mounted for both rotation and reciprocation in the barrel, elastic friction means secured on said shaft within the barrel to frictionally engage it loosely, and other means mounted movably on the shaft adapted to compress said friction means when the shaft is rotated in one direction to expand the friction means elastically to tightly engage the barrel to lock the shaft against relative longitudinal movements in the barrel.

2. In combination with the shaft of an instrument, a hollow closed handle therefor having a bearing aperture, said shaft traversing said aperture for both rotational and longitudinal movements therein, an elastic rubber body apertured centrally to receive the shaft therethrough, said shaft having a threaded end, and having a fixed abutment to engage one end of said body and a movable abutment to engage the opposite end of said body, and said movable abutment having an internally threaded opening to mesh it with the thread on the shaft, said body when uncompressed lightly engaging the handle permitting relative longitudinal movement of the shaft, and said movable abutment serving to clamp and compress said body to expand it radially when the shaft is rotated in one direction to tightly engage the handle to substantially prevent longitudinal movements of the shaft, said movable abutment during this operation being held by its slight frictional contact with the handle from turning when the shaft is thus rotated.

3. In combination with the shaft of an instrument, a hollow handle barrel closed at one end and having an apertured opposite closed end, said shaft traversing said aperture for both rotational and longitudinal movements, an elastic friction-head secured upon the inner end of the shaft to lightly contact circumferentially with the inner wall of the barrel, said shaft termination being threaded beyond said friction-head, said shaft having a fixed abutment thereon, and engaging one end of the friction-head, and a clamping-nut on said threaded end engaging the friction-head to compress it against the fixed abutment when the shaft is turned one way.

4. In combination, a hollow imperforate handle, a shaft extending thereinto and having both rotational and longitudinal movements, clamping bodies, one being fixed on

the shaft coaxially, the other having a central inwardly threaded aperture, the end of the shaft being threaded and the second mentioned clamping body seated for longitudinal movements on its thread, an elastic body centrally apertured to seat it on said shaft between and end-engaged by said clamping bodies, said elastic body engaging the inner wall of the handle, and the abutting parts of said clamping bodies and the interposed elastic body having counterpart mating concave and convex ends to clutch them together, whereby when the shaft is rotated in one direction the elastic body is held by slight peripheral friction against the inner wall of the handle against rotation, and the movable clamping body is drawn toward the fixed clamping body to compress the elastic body to expand it into tighter frictional contact with the handle circumferentially to tend to prevent longitudinal movements of the shaft relative to the handle due to the exercise of ordinary force upon the shaft.

In testimony whereof I affix my signature.

ALBERTO I. WOODRING.
